UNITED STATES PATENT OFFICE

GEORGE R. WILCOX, OF GREENFIELD, MASSACHUSETTS, ASSIGNOR TO GOODELL-PRATT COMPANY, OF GREENFIELD, MASSACHUSETTS, A CORPORATION OF MASSACHUSETTS

DESIGN FOR AN ELECTRIC DRILL

Application filed August 6, 1929. Serial No. 32,311. Term of patent 14 years.

To all whom it may concern:

Be it known that I, GEORGE R. WILCOX, a citizen of the United States, residing at Greenfield, in the county of Franklin and State of Massachusetts, have invented a new, original, and ornamental Design for Electric Drills, of which the following is a specification, reference being had to the accompanying drawing, forming part thereof.

Fig. 1 is a side elevation of an electric drill, showing my new design, and

Fig. 2 is an end elevation of the same.

I claim:

The ornamental design for an electric drill as shown.

GEORGE R. WILCOX.
